[57] CLAIM

The ornamental design for a central processor unit for a data processing system, as shown.

DESCRIPTION

FIG. 1 is a right front perspective view of a central processor unit for a data processing system incorporating our new design;

FIG. 2 is a left rear perspective view of the central processor unit of FIG. 1; and

FIG. 3 is a bottom plan of the central processor unit of FIG. 1.

FIG. 1

FIG. 2**FIG. 3**
